WILLIAM H. BROWN, OF SYRACUSE, NEW YORK, ASSIGNOR TO H. H. FRANKLIN MANUFACTURING COMPANY, OF SYRACUSE, NEW YORK, A CORPORATION OF NEW YORK.

ZERO-ELIMINATING MECHANISM FOR CALCULATING-MACHINES.

1,108,877. Specification of Letters Patent. Patented Sept. 1, 1914.

Application filed September 29, 1910, Serial No. 584,400.

To all whom it may concern:

Be it known that I, WILLIAM H. BROWN, of Syracuse, in the county of Onondaga and State of New York, have invented a certain 5 new and useful Zero-Eliminating Mechanism for Calculating Machines, of which the following is a specification:

My invention relates to calculating machines and particularly to means for moving the zero type of the inactive recording elements out of the printing line; and it consists in the combinations and constructions hereinafter set forth and claimed.

In describing this invention reference is 15 had to the accompanying drawing, in which like characters designate corresponding parts in all the views.

Figure 1 is an elevation partly in section, of a portion of a calculating machine, embodying my invention, the parts being shown in their normal position. Fig. 2 is a view similar to Fig. 1, parts being omitted and portions of the recording mechanism being shown in their positions occupied during the making of the record. Fig. 3 is a plan of parts seen in Fig. 2, parts of the printing mechanism being omitted. Fig. 4 is a section on line A—A Fig. 3. Figs. 5 and 6 are sections on line B—B, Fig. 3, a recording element being shown in its normal position in Fig. 5, and in its position assumed when the zero type thereof is out of the printing line in Fig. 6. Fig. 7 is a detail view of the parts for moving the zero type of the inactive recording elements out of the printing line. Fig. 8 is a view similar to Figs. 5 and 6 illustrating the position of the zero eliminating pawls after they have been shifted out of active position.

The illustrated embodiment of my invention comprises printing mechanism including a series of recording elements having type representing the numerals from zero to nine inclusive, the zero type being normally at the printing line, and the recording elements being movable into numerical positions and means for moving the inactive elements (to wit those elements to the left of the elements in which a number is set) for shifting the zero type thereof out of the

printing line and moving a blank into the printing line.

The recording elements 1 are here shown as wheels mounted side by side on a shaft 2, which is supported at its ends by side arms 55 3 of a frame 4 pivoted at 5 to the main frame 6 of the machine. Two additional wheels 7, similar in construction and operation to the wheels 1 are mounted on the shaft to the right of the series 1, for recording decimal fractions or "cents".

The wheels 1 and 7 are shown as toothed, and the teeth thereof as provided with type at their ends representing the numerals from zero to nine inclusive. Said wheels 1 and 7 65 are movable into numerical positions in any suitable manner and as here illustrated the frame 4 is movable on its pivot 5 for carrying the wheels 1 and 7 into and out of mesh with a series of toothed controlling elements, 70 one of which is illustrated at 8. These elements 8 are mounted on a shaft 9 and are movable about the axis of the shaft for imparting motion to the wheels 1 and 7 when the wheels 1, 7 and 8 are in mesh. The 75 operation of the wheels 1 and 7 by the elements 8 forms the subject matter of another application Sr. No. 565,197, filed June 6, 1910.

Suitable carrying over mechanism not 80 shown is usually associated with the wheels 1. The carrying over mechanism may be of any desirable form, size and construction, and one form of such mechanism forms the subject matter of my pending application, 85 Sr. No. 592227 filed Nov. 14, 1910.

A hammer or printing member, here shown as a cylindrical platen 10 co-operates with the recording elements 1 and 7 for printing a record on the sheet 11 extending 90 between the platen 10 and the elements 1, 7 and 8. As here shown the platen 10 supports the record sheet 11, is movable toward and from the recording elements 1 and 7 and is carried by a rocking frame 12 pivoted 95 at 13 to arms 14 which are mounted on the pivot 5 of the frame 4. The platen 10 is movable with the recording wheels into cooperation with the controlling elements 8, for making a record of the examples set up 100

in the elements 8, and is movable toward and from the wheels 1 and 7 for taking the total. A suitable ribbon 15 is interposed between the record sheet and the recording elements 1 and controlling elements 8.

The means for moving the inactive elements 1 and shifting the zero type thereof out of the printing line preliminary to the taking of the total record, comprises a series 10 of parts usually pawls 16, extending parallel to the recording series 1, one part for each wheel; each of the pawls 16 being normally engaged with one of the teeth of the corresponding elements 1 and being 15 movable out of its normal position by the corresponding element 1, when being rotated by one of the controlling elements 8, and one series being movable relatively to the other, in order that the unmoved pawls 20 engaged with the inactive elements 1, may cause said inactive elements to be rotated sufficiently from the position seen in Fig. 5 to carry the zero type into the position shown in Fig. 6.

25 The series of pawls 16 is preferably movable relatively to the series of recording elements 1, and these pawls 16 are mounted on a shaft 17 carried by a rocking frame or yoke 18 which is mounted on and movable about the shaft 2. The shaft 17 is formed with a lengthwise shoulder, or, feather 19, and each pawl 16 is formed with a relatively wide recess 20 for receiving the feather 19. This recess 20 permits the pawls 35 16 to have a limited movement about the shaft 17, out of their operative position. Springs 21 carried by said frame 18, engage arms 22 provided on the pawls 16 and force said pawls 16 into their normal position.

40 Each spring is formed with a rounding projection 23, and the arms 22 move from one side to the other side of the projection 23, when the pawls are shifted to their inoperative position by the corresponding wheel 1. 45 Each pawl 16 is formed with a laterally extending lug or shoulder 24 to be engaged by the next pawl to the left as seen in Fig. 7 which shows some of the pawls in rear elevation. When one of the pawls is moved by a calculating wheel all the pawls to the right thereof are moved out of operative position so that the zeros of the calculating elements to the right of that first operated will not be eliminated.

55 The means for moving the platen 10 toward and from the recording elements 1 and 7, and for moving the series of pawls relatively to the elements 1, comprises an operating lever 25 pivoted at 26 to the main frame 6 and connected to the oscillating frame 12 supporting the platen 10 and to the frame 18 supporting the pawls 16. The connections between the lever 25 and the frame 12 comprise a link 27 connected at

one end at 28 to said lever 25 and at its 65 other end to the frame 12. So far as this invention is concerned the link 27 may be connected directly to the frame 12, but is shown as connected at 29 to angular lever 30 pivoted on the pivot 13 of the frame 12, 70 and connected by a link 31 to the end of the platen 10 at 32, at a point eccentric to the axis of the platen. When the lever 25 is depressed the link 27 moves the lever 30 on the pivot 13, and thereby rotates the 75 platen 10 about its axis, the rotation thereof being limited by a stop 33 movable into and out of engagement with the end walls of a recess 34 formed in the platen 10. As is obvious when the rotation of the platen is 80 limited, the additional movement of the lever 25 will rock the frame 12. The rotation referred to of the platen is for the purpose of bringing the foot of the column of figures recorded on the sheet 11 from the 85 elements 8 near the printing line of the series of recording elements 1 and 7, in order that a space will not intervene between the foot of said column of figures and the total. The means for moving the platen 90 10 forms the subject matter of my pending application, Sr. No. 474,931, filed Jan. 29, 1909. The operating lever 25 is provided with an upwardly extending arm 35 which moves into and out of engagement with an 95 arm 36 projecting downwardly from the rocking frame 18, so that, as the lever 25 is depressed the arm 36 will be moved forwardly rocking the frame 18 downwardly against the action of a spring 37, Fig. 3, 100 and causing any pawls 16 not moved out of their normal position, to actuate the inactive elements as before explained.

105 After the total has been taken the recording elements 1 and 7 may be cleared or moved to their starting position, so that all the zero type are at the printing line by rotating the shaft 2, said shaft being connected to the recording elements 1 and 7, by friction ratchets, each consisting of an internal series of teeth 28 provided on each of the elements 1 and 7, and spring-pressed balls 39 arranged at the opposite ends of transverse passages in the shaft 2. The 110 pawls 16 are reset in their normal position after the recording elements 1 have been cleared, by rocking the shaft 17. As here shown, the shaft 17 is provided with a rock arm 40 which is arranged in the path of the cam or arm 41 mounted on a rock shaft 42. 115 Said arm 41 normally occupies the position shown in Fig. 4, and is movable upwardly engaging the rock arm 40 and moving the pawls 16 into operative position. However, if the pawls, remained in inoperative positions at this stage of the operation of the mechanism the turning of the shaft 2 to clear the machine would be prevented, and 120 125

therefore said arm 41 passes to the opposite side of the arm 40 and the rock shaft 17 is moved back to its normal position by a spring 43 acting on an arm 44 on said shaft 17. On the return of the arm 41, it strikes the arm 40 and turns the pawls into operative positions. Usually the clearing of the recording elements 1 and 7 and the resetting of the pawls 16, is effected by the shaft 10 42 and these clearing and resetting operations are so timed, that during the motion of the shaft 42 carrying the rock arm 41 upwardly, the shaft 2 is being rotated to carry the elements 1 to their starting position and that during the return movement of said arm 41, the pawls 16 are reset. This shaft 42 may be connected to the shaft 2 in any suitable manner here shown as by a power transmitting element 45 coacting with 20 a gear 46 on the shaft 2. For full description of this connection reference is had to my pending application, Sr. No. 592,927 filed Nov. 14, 1910, and as in my pending application Sr. No. 741,786, filed Jan. 13, 1913.

25 The shaft 42 is actuated by a driving shaft 47 having a suitable hand lever, not shown, and also having a toothed element 48 mounted thereon which meshes with a gear 49 mounted on the shaft 42. The operation of 30 the shaft 42 therefore first clears the recording elements 1 and 7 and then resets the pawls 16.

35 My calculating machine is also formed with means for printing a character to distinguish the total record. This means is here shown as a type 50 carried at the end of an arm 51 mounted on and rotatable with the shaft 2, said type 50 being located at the right end of the series of recording elements 1 and 7 and being normally located 40 in the printing line. As the only movement of the shaft 2 is one rotation to clear the recording elements 1, the type carrying arm 50 is fixed in the normal operation of 45 the wheels 1.

What I claim is:

1. In a calculating machine, printing mechanism comprising a series of recording elements, each having type representing numerals including a zero type, the zero type being normally at the printing line, and the elements being capable of rotating complete revolutions in succession to carry the type into numerical positions, and means for actuating the inactive elements remaining to the left of those elements in which a number has been set, for moving the zero type of said inactive elements out of the printing line, substantially as and for the purpose 60 described.

2. In a calculating machine, printing mechanism comprising a series of recording elements, each having type representing numerals including a zero type, the zero type

being normally at the printing line, and the elements being rotatable for carrying the type into numerical positions, and members for actuating the inactive elements remaining to the left of those elements in which a number has been set, for moving the zero type of said inactive elements out of the printing line, the members being individual to the elements and each member having means for operating the next member to the right, substantially as and for the purpose specified.

3. In a calculating machine, printing mechanism comprising a series of recording elements, each having type representing numerals including a zero type, the zero type being normally at the printing line, and the elements being rotatable for carrying the type into numerical positions, and members for actuating the inactive elements remaining to the left of those elements in which a number has been set, for moving the zero type of said inactive elements out of the printing line, the members being individual to the elements and each member having means for operating the next member to the right, and each member being operable out of operative position by its companion recording element, substantially as and for the purpose set forth.

4. In a calculating machine, printing mechanism including a series of elements each having type representing numerals including a zero type, the zero type being normally at the printing line, and the elements being rotatable for carrying the type into printing position and being capable of making complete rotations, and a member movable toward and from said elements for effecting the making of a record, members for actuating the inactive elements remaining to the left of those elements in which a number has been set, the members being individual to said elements and operable thereby and each having a part for operating the member to the right, and an operating part connected to the printing member and to the actuating members for the inactive element, substantially as and for the purpose described.

5. In a calculating machine, and in combination, a shaft, a series of recording elements rotatably mounted thereon and each having type representing numerals including a zero type, the zero type being normally at the printing line, and the elements being movable about said shaft into numerical positions, means for retarding the movement of the elements about the shaft, and means operating through the engagement of the retarding means with the recording elements for actuating the inactive elements remaining to the left of those elements in which a number has been set, for moving the zero

type of said inactive elements out of the printing line, substantially as and for the purpose set forth.

6. In a calculating machine, printing mechanism comprising a series of recording elements, each having type representing numerals including a zero type, the zero type being normally at the printing line, and the elements being movable into numerical positions, and means for actuating the inactive elements remaining to the left of those elements in which a number has been set, for moving the zero type of said inactive elements out of the printing line, the actuating means for the inactive elements comprising a series of parts, one part for each recording element, said parts being normally in position to coöperate with the corresponding elements and being movable out of such position by the corresponding elements when said elements are moved into numerical positions, substantially as and for the purpose specified.

7. In a calculating machine, printing mechanism comprising a series of recording elements, each having type representing numerals including a zero type, the zero type being normally at the printing line, and the elements being movable into numerical positions, and a series of parts, one part for each recording element, said parts being normally in position to coöperate with the corresponding elements and being movable out of such position by the corresponding elements when said elements are moved into numerical positions, one series being movable relatively to the other for causing the parts remaining in their normal position to actuate the corresponding elements and move the zero type thereof out of the printing line, substantially as and for the purpose set forth.

8. In a calculating machine, printing mechanism comprising a series of recording elements, each having type representing numerals including a zero type, the zero type being normally at the printing line, and the elements being movable into numerical positions, and a series of parts, one part for each recording element, the parts being normally in position to coöperate with the corresponding elements and being movable out of such position by the corresponding elements when said elements are moved into numerical positions, and each part being connected to the next part to the right for moving said part to the right out of its normal position when the part to the left is moved by the corresponding element out of its normal position, one series being movable relatively to the other for causing the parts remaining in their normal position to actuate the corresponding elements and move the zero type thereof out of the printing line, substantially as and for the purpose described.

9. In a calculating machine, printing mechanism comprising a series of recording elements, each having type representing numerals including a zero type, the zero type being normally at the printing line, and the elements being movable into numerical positions, and a series of parts, one part for each recording element, the parts being normally in position to coöperate with the corresponding elements, and being movable out of such position by the corresponding elements when said elements are moved into numerical positions, and each part having a laterally-extending lug for engaging and operating the next part to the right and thereby moving the part to the right out of its normal position when the part to the left is moved out of its normal position, and one series being movable relatively to the other, substantially as and for the purpose specified.

10. In a calculating machine, printing mechanism comprising a series of recording elements, each having type representing numerals including a zero type, the zero type being normally at the printing line, and the elements being movable into numerical positions, and a series of spring-pressed pawls for normally engaging, respectively, the recording elements, the pawls being movable out of their normal position by the corresponding elements when said elements are moved into numerical positions, one of said series being movable relatively to the other, substantially as and for the purpose set forth.

11. In a calculating machine, printing mechanism comprising a series of recording elements, each having type representing numerals including a zero type, the zero type being normally at the printing line, and the elements being movable into numerical positions, and a series of spring-pressed pawls for normally engaging, respectively, the recording elements, the pawls being movable out of their normal position by the recording elements when said elements are moved into numerical positions, each pawl having means for tripping the next pawl to the right when the pawl to the left is operated by the corresponding recording element, and one series being movable relatively to the other series, substantially as and for the purpose described.

12. In a calculating machine, printing mechanism comprising a series of recording elements, each having type representing numerals including a zero type, the zero type being normally at the printing line, and the elements being movable into numerical positions, a series of spring-pressed pawls for normally engaging, respectively, the recording elements, the pawls being movable out of their normal position by the corresponding elements when said elements are moved

10 into numerical positions, each pawl having
11 a laterally-extending lug for tripping the
12 next pawl to the right when the pawl to the
13 left is operated by the corresponding re-
14 cording element, and one series being mov-
15 able relatively to the other series, substan-
16 tially as and for the purpose specified.

17 13. In a calculating machine, printing
18 mechanism comprising a series of recording
19 elements, each having type representing nu-
20 merals including a zero type, and each hav-
21 ing a tooth, the zero type being normally at
22 the printing line, and the recording ele-
23 ments being movable into numerical posi-
24 tions, and a series of spring-pressed pawls
25 for normally engaging the teeth of the re-
26 cording elements, respectively, the pawls be-
27 ing movable out of their normal position by
28 the corresponding elements when said ele-
29 ments are moved into numerical positions,
30 and one series being movable relatively to
31 the other series, substantially as and for
32 the purpose set forth.

33 14. In a calculating machine, printing
34 mechanism comprising a series of recording
35 elements, each having type representing nu-
36 merals including a zero type, the zero type
37 being normally at the printing line, and the
38 recording elements being movable into
39 numerical positions, a shaft extending paral-
40 lel to the series of the recording elements,
41 a series of spring-pressed pawls mounted on
42 the shaft and normally engaging the re-
43 cording elements, respectively, the pawls be-
44 ing movable about the shaft out of their
45 normal position by the corresponding ele-
46 ment when said elements are moved into
47 numerical positions, and one series being
48 movable relatively to the other series, sub-
49 stantially as and for the purpose described.

50 15. In a calculating machine, printing
51 mechanism comprising a series of recording
52 elements movable about an axis, each having
53 type representing numerals including a zero
54 type, the zero type being normally at the
55 printing line, and the elements being mov-
56 able into numerical positions, means for ac-
57 tuating the inactive elements remaining to
58 the left of those elements in which a number
59 has been set, for moving the zero type of
60 said inactive elements out of the printing
61 line, the actuating means for the inactive
62 elements comprising a series of parts coact-
63 ing, respectively, with said elements, said
64 parts being movable as one body about the
65 axis of the recording element, substantially
as and for the purpose specified.

66 16. In a calculating machine, a shaft,
67 printing mechanism comprising a series of
68 recording elements mounted on the shaft,
69 each having type representing numerals in-
70 cluding a zero type, the zero type being nor-
71 mally at the printing line, and the elements
72 being movable about the axis of the shaft
73 into numerical positions; means for actuat-

74 ing the inactive elements remaining to the
75 left of those elements in which a number has
76 been set, for moving the zero type of said
77 inactive elements out of the printing line,
78 said means comprising a frame mounted on
79 the shaft and movable about the axis there-
80 of, a series of pawls supported by the frame
81 and coöperating, respectively, with the re-
82 cording elements, and means for rocking the
83 frame about the axis of the shaft, substan-
84 tially as and for the purpose set forth.

85 17. In a calculating machine, a shaft,
86 printing mechanism comprising a series of
87 recording elements mounted on the shaft,
88 each having type representing numerals in-
89 cluding a zero type, the zero type being nor-
90 mally at the printing line, and the elements
91 being movable about the axis of the shaft
92 into numerical positions, means for actuat-
93 ing the inactive elements remaining to the
94 left of those elements in which a number has
95 been set, for moving the zero type of said
96 inactive elements out of the printing line,
97 said means comprising a frame mounted on
98 the shaft and movable about the axis there-
99 of, a series of pawls supported by the frame
100 and coöperating, respectively, with the re-
101 cording elements, said pawls being normally
102 in position to coöperate with the correspond-
103 ing elements and being movable out of such
104 position when the corresponding elements
105 are moved into numerical positions; and
106 means for rocking the frame about the axis
107 of the shaft, substantially as and for the
108 purpose described.

109 18. In a calculating machine, a shaft,
110 printing mechanism comprising a series of
111 recording elements mounted on the shaft,
112 each having type representing numerals in-
113 cluding a zero type, the zero type being nor-
114 mally at the printing line, and the elements
115 being movable about the shaft into numeri-
116 cal positions, means for actuating the in-
117 active elements remaining to the left of those
118 elements in which a number has been set; for
119 moving the zero type of said inactive ele-
120 ments out of the printing line, the actuating
121 means comprising a frame mounted on the
122 shaft, and movable about the axis thereof, a
123 shaft carried by the frame and extending
124 parallel to the first-mentioned shaft, a series
125 of pawls mounted on the second-named shaft
126 for coöperating with the recording elements
127 respectively, said pawls normally engaging
128 the recording elements and being movable
129 out of engagement therewith by the record-
130 ing elements when moving into numerical
131 positions, and means for rocking the frame
132 about the axis of the first-mentioned shaft,
133 substantially as and for the purpose speci-
134 fied.

135 19. In a calculating machine, printing
136 mechanism comprising a series of recording
137 elements, each having type representing nu-
138 merals including a zero type, the zero type 130

- being normally at the printing line, and the elements being movable into numerical positions, a shaft extending parallel to the series of recording elements, a series of spring-pressed pawls mounted on the shaft and normally in position to engage the recording elements respectively, the pawls being movable about the shaft a limited distance out of their normal positions by the recording elements when moving into numerical positions, and each pawl being connected to the pawl to the right for moving said pawl to the right out of its normal position when the pawl to the left is moved out of its normal position, one series being movable relatively to the other series for causing the unmoved pawls to actuate the inactive recording elements remaining to the left of those in which a number has been set, in order to move the zero type of said inactive elements out of the printing line, substantially as and for the purpose set forth.
20. In a calculating machine, printing mechanism comprising a series of recording elements, each having type representing numerals including a zero type, the zero type being normally at the printing line, and the elements being movable into numerical positions, a shaft extending parallel to the series of recording elements, a series of spring-pressed pawls mounted on the shaft and being normally in position to engage the recording elements respectively, the pawls being movable about the shaft out of their normal position by the recording elements when moving into numerical positions, and each pawl being connected to the next pawl to the right for moving the next pawl to the right out of its normal position, one series being movable relatively to the other series for causing the unmoved pawls to actuate the inactive recording elements remaining to the left of those in which a number has been set, in order to move the zero type of said inactive elements out of the printing line, and means for moving the shaft about its axis to rest the pawls in their normal position, substantially as and for the purpose described.
50. 21. In a calculating machine, printing mechanism comprising a series of recording elements, each having type representing numerals including a zero type, the zero type being normally at the printing line, said recording elements being movable into numerical positions, a shaft extending parallel to the series of recording elements and having a shoulder extending lengthwise thereof, a series of spring-pressed pawls mounted on the shaft and being normally in position to engage the recording elements, respectively, the pawls being formed with a relatively wide recess for receiving said shoulder and being movable about the shaft out of their normal positions by the recording elements when moved in numerical positions, one series being movable relatively to the other series for causing the unmoved pawls to actuate the inactive recording elements remaining to the left of those in which a number has been set, in order to move the zero type of said inactive elements out of the printing line, and means for rocking the shaft to reset the pawls, substantially as and for the purpose specified.
22. In a calculating machine, a shaft, printing mechanism comprising a series of recording elements mounted on and movable about the shaft, each recording element having type representing numerals including a zero type, the zero type being normally at the printing line, and the elements being movable about the shaft into numerical positions, a frame mounted on the shaft and movable about the axis of the shaft, a shaft supported by the frame, extending parallel to the first-mentioned shaft, the second-named shaft being formed with a shoulder extending lengthwise thereof, a series of spring-pressed pawls mounted on the second-mentioned shaft and being normally in position to engage the recording elements, respectively, the pawls being formed with a relatively wide recess for receiving said shoulder, and being movable about the second-named shaft out of their normal position by the recording elements when moving into numerical positions, each pawl having a laterally-extending dug for engaging the next pawl to the right and moving said pawl to the right out of engagement with the corresponding recording element when the pawl to the left is moved out of its operative position, means for rocking the frame, and means for rocking the pawl shaft for resetting the pawls, substantially as and for the purpose set forth.
23. In a calculating machine, and in combination, a plurality of recording wheels of different denominations, each wheel being provided with a series of numbers, a platen, means for effecting relative movement between the latter and the wheels for taking an impression, and means including a device individual to each wheel for engaging therewith and moving the same to carry a blank space thereon to the printing point during the operation of the aforesaid means for effecting relative movement, each wheel on the advancement thereof to bring a number thereon to the printing point shifting out of operative position the said individual device associated therewith and the individual device associated with each of the wheels of the lower denomination, substantially as and for the purpose described.
24. In a calculating machine, and in combination, a plurality of wheels of different

denominations, each provided with a series of peripherally arranged digits and the character naught, said wheels normally resting with the last-named character at the printing line, means including a device individual to each wheel for engaging therewith for moving the same to carry the last-named character away from the printing line, means for advancing a selected wheel to bring one of the digits thereon to the printing point, said movement of the wheel shifting the individual device associated therewith out of operative position, and means for correspondingly moving the individual device associated with each of the wheels of lower denomination, substantially as and for the purpose specified.

25. In a calculating machine, printing mechanism including two members, one member comprising a series of recording elements, each having type representing numerals including a zero type, the zero type being normally at the printing line, and the elements being movable into numerical positions, and the other member comprising a platen for coöperating with said elements, said members being movable relatively to each other for effecting the making of a record, means for actuating the inactive elements remaining to the left of those elements in which a number has been set, for moving the zero type of said inactive elements out of the printing line, the actuating means for the inactive elements comprising a series of parts coating, respectively, with said elements, and one series being movable relatively to the other for effecting the actuation of the inactive elements, and an operating part connected to the movable member of the printing mechanism and to the movable series for successively actuating one series relatively to the other series and moving one member relatively to the other, substantially as and for the purpose set forth.

45. 26. In a calculating machine, printing mechanism including two members, one member comprising a series of recording elements, each having type representing numerals including a zero type, the zero type being normally at the printing line, and the elements being movable into numerical positions, and the other member comprising a platen coöperating with said elements, one of said members being movable relatively to the other member for effecting the making of a record, means for actuating the inactive elements remaining to the left of those elements in which a number has been set, for moving the zero type of said inactive elements out of the printing line, the actuating means for the inactive elements comprising a series of parts coating, respectively, with said elements, said series of parts being movable relatively to the series of recording elements, and an operating member connected to the series of parts and to the movable printing member, for successively moving said series of parts relatively to the series of recording elements and moving said printing member relatively to the recording elements, substantially as and for the purpose set forth.

60. 27. In a calculating machine, printing mechanism including a series of recording elements, each having type representing numerals including a zero type, the zero type being normally at the printing line, and the elements being movable into numerical positions, and a member movable relatively to said series of recording elements for effecting the making of a record, means for actuating the inactive elements remaining to the left of those in which a number has been set, for moving the zero type of said inactive elements out of the printing line, the actuating means for the inactive elements comprising a series of parts coating, respectively, with said elements, and one series being movable relatively to the other for effecting the actuation of the inactive elements, and an operating member connected to the printing member and to the movable series for successively actuating the movable series relatively to the other series and the movable printing member relatively to the recording elements, substantially as and for the purpose described.

28. In a calculating machine, printing mechanism including a series of recording elements, each having type representing numerals including a zero type, the zero type being normally at the printing line, and the elements being movable into numerical positions, and a member movable relatively to said series of recording elements for effecting the making of a record, means for actuating the inactive elements remaining to the left of those elements in which a number has been set, for moving the zero type of said inactive elements out of the printing line, the actuating means for the inactive elements comprising a series of parts coating, respectively, with said elements, said series of parts being movable relatively to the series of recording elements, and an operating member connected to the series of parts and to the movable printing member, for successively moving said series of parts relatively to the series of recording elements and moving said printing member relatively to the recording elements, substantially as and for the purpose set forth.

29. In a calculating machine, a shaft, printing mechanism including a series of recording elements mounted on and movable about the shaft, each having type representing numerals including a zero type, the

zero type being normally at the printing line, and the elements being movable about the shaft into numerical positions, and a member movable relatively to the recording elements for effecting the making of a record, a rocking frame mounted on the shaft and movable about the axis thereof, a series of pawls carried by said frame for coöperating with the recording elements, said 10 pawls normally engaging the recording elements and being movable out of engagement therewith when the corresponding elements are moved into numerical positions, each pawl being connected to the pawl to 15 the right thereof when being moved out of its normal position and an operating part connected to the frame and to the printing member for successively moving the frame about the shaft and moving said member 20 relatively to the recording elements, substantially as and for the purpose described.

30. In a calculating machine, printing mechanism including a series of recording elements, each having type representing numerals including a zero type, the zero type being normally at the printing line, and the elements being movable into numerical positions, a rocking frame and a platen carried by the rocking frame and movable therewith 25 relatively to the recording elements, means 30 for actuating the inactive elements remaining to the left of those elements in which a number has been set, for moving the zero type of said inactive elements out of the 35 printing line, the actuating means for the inactive elements comprising a series of parts coacting, respectively, with said elements, and an operative part connected to the frame and to the actuating means for the inactive 40 elements for successively moving said actuating means and rocking the said frame, substantially as and for the purpose specified.

31. In a calculating machine, printing mechanism comprising a series of recording elements, each having type representing numerals including a zero type, the zero type being normally at the printing line, and the elements being movable into numerical positions, a rocking frame and a member carried by said frame and movable therewith 45 relatively to the recording elements for making a record, means for actuating the inactive elements remaining to the left of those elements in which a number has been set, for 50 moving the zero type of said inactive elements out of the printing line, said means comprising a rocking frame, and a series of pawls supported by the frame and coöperating, respectively, with said elements, and 55 means for rocking the pawl frame and the printing member frame successively, substantially as and for the purpose set forth.

32. In a calculating machine, printing mechanism including a series of recording

elements, each having type representing the numerals from zero to nine inclusive, the zero type being normally at the printing line, and the elements being movable into numerical positions, a rocking frame and a platen carried by the rocking frame and movable therewith toward and from the series of recording elements, means for actuating the inactive elements remaining to the left of those elements in which a number has been set, for moving the zero type of said 65 inactive elements out of the printing line, the actuating means comprising a rocking frame, and a series of pawls carried by the second-named rocking frame and coacting, respectively, with said elements and an operating part connected to the rocking frames, substantially as and for the purpose described.

33. In a calculating machine, a series of toothed controlling elements, printing mechanism comprising a series of toothed recording elements for meshing with the controlling elements and being normally out of mesh therewith, teeth of the recording elements having type at their ends representing numerals including a zero type, the zero type of the recording elements being normally at the printing line of the recording series and the recording series being movable into and out of mesh with the controlling series, a printing member movable with the recording series toward and from the controlling series, the printing member being also movable at will relatively to the recording series, means for actuating the inactive elements of the recording series remaining to the left of those elements in which a number has been set by the controlling series, for moving the zero type of said inactive elements out of the printing line of the recording series, and an operating part connected to the printing member and to the actuating means for the inactive elements for successively operating said actuating means and moving the printing member toward and from the recording elements, substantially as and for the purpose specified.

34. In a calculating machine, printing mechanism comprising a series of recording elements, each having type representing numerals including a zero type, the zero type being normally at the printing line and the elements being movable into numerical positions, means for actuating the inactive elements remaining to the left of those elements in which a number has been set, for moving the zero type of said inactive elements out of the printing line, means for moving the active elements to their normal position, and means for resetting the actuating means for the inactive elements, substantially as and for the purpose set forth.

35. In a calculating machine, a shaft,

printing mechanism comprising a series of recording elements mounted on the shaft, each having type representing numerals including a zero type, the zero type being normally at the printing line, and the elements being movable about the axis of the shaft into numerical positions, means for actuating the inactive elements remaining to the left of those elements in which a number has been set, for moving the zero type of said inactive elements out of the printing line, means for rotating the shaft and recording elements together for returning the recording elements to their normal position, and means for also resetting the actuating means for the inactive elements, substantially as and for the purpose described.

36. In a calculating machine, a shaft, printing mechanism, comprising a series of recording elements mounted on the shaft and movable about the axis thereof, each element having type representing numerals including a zero type, the zero type being normally at the printing line, and the elements being movable about the axis of the shaft into numerical positions, means for actuating the inactive elements remaining to the left of these elements in which a number has been set, for moving the zero type of said inactive elements out of the printing line, said means including a shaft extending parallel to the first-named shaft, and a series of pawls mounted on the second-named shaft and coöperating, respectively, with the recording elements, the pawls being movable about the second mentioned shaft, a limited distance out of their normal position by the movement of the recording elements into numerical positions, and means for rotating the first-mentioned shaft and recording elements together for moving the recording elements to their normal positions and for rocking the pawl-shaft for resetting the pawls, substantially as and for the purpose specified.

45. 37. In a calculating machine, printing mechanism comprising a series of recording elements, each having type representing numerals including a zero type, the zero type being normally at the printing line, means for actuating the inactive elements remaining to the left of those elements in which a number has been set, for moving the zero type of said inactive elements out of the printing line, and means for moving the active elements to their normal position and thereby clearing the recording elements and for resetting the actuating means, the second-mentioned means comprising a shaft connected to the recording elements and to the actuating means for the inactive elements, substantially as and for the purpose set forth.

38. In a calculating machine, a shaft, printing mechanism comprising a series of

recording elements mounted on the shaft, each having type representing numerals including a zero type, the zero type being normally at the printing line, and the elements being movable about the axis of the shaft into numerical positions, means for actuating the inactive elements remaining to the left of those in which a number has been set, for moving the zero type of said inactive elements out of the printing line, and means for rotating the shaft for returning the recording elements to their normal position and thereby clearing the recording elements and for also resetting the actuating means for the inactive elements, the clearing and resetting means comprising a shaft arranged parallel to the former shaft and having means for engaging the former shaft, substantially as and for the purpose described.

39. In a calculating machine, a plurality of wheels each carrying a series of numbers, means for rotating the wheels for bringing the desired numbers thereon to the printing point, a movable frame, a rock shaft mounted therein, a series of pawls mounted on said shaft movable therewith and movable independently thereof to occupy two positions, one in and the other out of engagement with the wheels, coöperating means between said shaft and pawls for limiting the extent of such independent movement, springs tending to retain the pawls at either end of the path of said independent movement, each of said pawls coöperating with one of said wheels, and being movable thereby toward its disengaged position, means operating on the movement of one of said pawls into disengaged position for correspondingly shifting the pawls associated with the wheels of lower denomination than the wheel last-named, and means for moving said frame to shift through the remaining pawls the wheels with which they are associated for bringing blank spaces thereon to the printing point, substantially as and for the purpose specified.

40. In a calculating machine, a shaft, a plurality of wheels mounted thereon and each provided with a plurality of numerical characters, connection between the shaft and the wheels for permitting the rotation of the latter about the shaft for bringing desired characters to the printing line, and for rotating the wheels when unretarded with the shaft in the rotation of the latter, and a total indicating character connected to the shaft for rotation therewith, substantially as and for the purpose set forth.

41. In a calculating machine, a shaft, a series of movable recording elements mounted on and movable about the shaft, each element having type representing numerals and the elements being movable about the shaft into numerical positions, an arm mounted

on and movable with the shaft, said arm having a type normally arranged in the printing line, means for connecting the elements and shaft together to rotate as one body, and said shaft and elements being rotatable together for moving the elements from numerical positions to their normal positions, substantially as and for the purpose specified.

In testimony whereof, I have hereunto signed my name in the presence of two attesting witnesses, at Syracuse, in the county of Onondaga, in the State of New York, this 19th day of Sept. 1910.

WILLIAM H. BROWN.

Witnesses: S. DAVIS and G. B. SMITH.
